UNITED STATES PATENT OFFICE.

HARRY H. KLEIN, OF NEW YORK, N. Y.

HAIR WAVER.

1,425,527.

Specification of Letters Patent. Patented Aug. 15, 1922.

Application filed June 21, 1921. Serial No. 479,184.

To all whom it may concern:

Be it known that I, HARRY H. KLEIN, a citizen of the United States, and resident of the city of New York, in the county of New York and State of New York, have invented a certain new and useful Hair Waver, of which the following is a specification.

This invention relates to hair wavers or hair curlers of the type which, as ordinarily made and used, comprises substantially a flexible bar, around the middle portion of which the hair is curled or wound, and the end portions of said bar are then bent over so as to secure the curled hair in place.

The principal object of my invention is to provide a simplified, inexpensive, conveniently and economically manufacturable, conveniently and efficiently utilizable, light, strong, durable, and improved hair waver.

Other objects and advantages will hereinafter appear.

In the accompanying drawings,—

Fig. 1 shows an elevation of the hair waver.

Fig. 2 shows an elevation of a modification of the hair waver.

Fig. 3 shows an elevation of a covered ring body, out of which this hair waver is manufactured.

Figs. 4, 5, 6, 7, and 8, show modified structures of the ring shown in Fig. 3.

Fig. 9 is a cross-sectional view showing a modification of the ring shown in Fig. 3.

The waver 1, as shown in Fig. 1, consists of a ring 2, Fig. 3, which is made of a single piece of suitable metal wire 3, the extremities of which are welded together, so as to form a continuous ring without indication of any kind of joint. Said ring is covered by

any suitable covering 4, such as a fabric, rubber, celluloid, or any other suitable material, and by any suitable means, as, for example, by means of winding a thread 5 around the wire 3 in the manner shown at

6. The ring 2 is then collapsed to the configuration shown in Fig. 2 and is twisted to form a rope-like body 7 which constitutes the body of the waver Fig. 1, and each extremity of said waver-body is formed into an

eye 8, which is preferably somewhat enlarged, as shown. The ring 2 may be japanned or otherwise protectively coated to render it convenient and safe for serving the above purpose, and when finally configurated in the form shown in Fig. 1 it con-

stitutes the completed hair waver. This completed hair waver may be utilized by curling the hair around its middle portion 9 and then bending its ends 9^a upon the curled hair in the well known manner. 60

According to the modification shown in Fig. 6 the terminals 10 of the wire 3 of the ring 2, instead of being welded together, as shown in Fig. 3, are merely brought end to end as shown at 11 and the extremities of the wire are then secured together by a metal tube 12 being slipped over the terminals 10, and the same may be soldered to the terminals or held thereto by a frictional or tight fit. In the modification shown in Fig. 5, 70 the terminals 10, of the wire 3 of ring 2, are secured together by means of twisting them, together, as shown at 13, and in the modification shown in Fig. 7 these terminals are secured together by the socket construction 14. 75 In the modification shown in Fig. 4, the terminals 10 of the wire 3 of the ring 2 are secured together, by being lapped over each other at 15 and soldered together. If desired this soldering may 80 be omitted, in which case the terminals 10 could be secured to each other by any covering 4 for the ring 2, and preferably by the type of covering shown in Fig. 3, wherein the thread 5 can be wound around the ring 85 2 and also around its terminals 10, Fig. 4. In the modification shown in Fig. 8 the ring 2 consists of a single piece of wire 3 which is wound around a plurality of times, and the terminals 10 of the wire may be secured 90 to the ring body, either by means of soldering them to the ring-body 3 or winding the thread 5 shown in Fig. 3 therearound or by the use of any other covering means. 95

According to the modification shown in Fig. 2, the ring 2, instead of being twisted to form the body shown in Fig. 1, the same is simply collapsed to form the slotted bar 16 as shown, which bar thus constitutes the waver, and the same may be utilized in the 100 regular manner.

The winding of the thread 5 around the wire 3 may be done once, as shown in Fig. 3, or in two or more layers, as shown in the cross-sectional view, Fig. 9. It will be noted 105 that although this waver is made entirely of wire, or covered wire, there is no wire terminal showing anywhere thereon, and the two extremities 8 of the waver are precisely alike in character, and consist of completely 110

closed eye-shaped terminals 8. It will be evident that although the ring 2 is here shown as made initially from a straight wire, by either welding or otherwise securing the terminals of such wire, the same may be also made by stamping a ring out of sheet metal or casting the same.

Variations may be resorted to within the scope of the invention, and portions of the 10 improvements may be used without others.

Having thus described my invention, I claim:—

1. An endless piece of wire twisted upon itself to form a hair waver.
- 15 2. The method of producing a hair waver consisting of welding a piece of wire into a

ring, and then twisting said ring upon itself to form the hair waver.

3. A ring of covered wire twisted upon itself to form a hair waver.

4. A ring of wire configurated to form a hair waver.

5. The method of producing a hair waver consisting of welding a piece of wire into a ring, and then configurating said ring to 25 form the hair waver.

6. A ring of covered wire configurated to form a hair waver.

Signed at the city of New York, in the county of New York, and State of New 30 York, this 20th day of June, A. D. 1921.

HARRY H. KLEIN.
